UNITED STATES PATENT OFFICE.

MOSES J. DORAN, OF PIERPONT, OHIO.

GRAIN-CLEANER ATTACHMENT FOR THRASHING MACHINES.

Application filed April 21, 1921. Serial No. 463,259.

To all whom it may concern:

Be it known that I, MOSES J. DORAN, a citizen of the United States of America, residing at Pierpont, in the county of Ash-
5 tabula and State of Ohio, have invented cer-
tain new and useful Improvements in
Grain-Cleaner Attachments for Thrashing
Machines, of which the following is a speci-
fication.

10 The primary object of the present invention is to provide a grain-separating spout adapted for oscillatory suspension within a thrashing machine spout for the reception of the thrashed grain as it leaves the ma-
15 chine and whereby clean grain may be bagged at the thrashing machine which will not require further cleaning or separating.

A further object of the invention is the provision of an auxiliary spout for receiv-
20 ing the grain from a thrashing machine for separating and conducting clean grain to one side of the machine and the waste to the other side thereof, my device being adapted for agitation by connection with a
25 movable part of the machinery of the thrashing machine with which the device is employed.

A still further object of the invention is to provide a separating spout that is simple
30 in construction, easy and inexpensive to manufacture and may be easily installed upon an ordinary thrashing machine for the final separation and cleaning of the grain from the chaff.

35 With these objects in view the invention consists of the combination and arrangement of parts hereinafter more fully described in connection with the accompanying drawing and in which like reference characters designate corresponding parts throughout the several views.

In the drawing,

Figure 1 is a side elevational view of the invention illustrating in dotted lines a man-
45 ner of suspending and oscillating the same,

Figure 2 is a central longitudinal sec-
tional view thereof,

Figure 3 is a top plan view of the same,

Figure 4 is a transverse sectional view
50 taken upon line IV—IV of Figure 1, and

Figure 5 is a similar sectional view taken upon line V—V of Figure 1.

Referring more in detail to the drawing, it will be understood that my invention is
55 an attachment for use within the grain spout of a thrashing machine and broadly

consists of an auxiliary spout having oppo-
site sides 10 and 11 with an inclined bottom
12, and a sieve or screen 13 oppositely in-
clined above the bottom 12, for receiving 60
grain directly thereon. The sides 10 and
11 are adjustably connected together by four
transverse bolts 14 having heads 15 out-
wardly of the side 11 with winged nuts 16
threaded upon the opposite ends of the 65
bolts outwardly of the side 10.

The screen 13 is pivoted adjacent its higher end 17 upon one of the upper bolts 14 and extends between the sides 10 and 11 beneath the corresponding upper bolt at 70 the opposite end of the spout while the bot-
tom board 12 rests with its lower end 18 upon the bolt 14 beneath the end 17 of the screen and with the upper end of the bottom 12 between the sides 10 and 11 at a con-
siderable distance inwardly of the lower end 75 of the screen 13. The bottom 12 and screen 13 are maintained adjustably inclined in opposite directions by tightening the nuts 16 upon the bolts 14, thereby securing the 80 same between the sides 10 and 11.

The screen being adapted for the recep-
tion of grain, the device is designed for sus-
pension for ready oscillation within the dis-
charge spout of a thrashing machine and 85 suspending members such as hooks 19 illus-
trated by dotted lines may be employed for
this purpose engaging beneath the upper
corner extensions 20 of the sides 10 and 11.
The draft from the thrashing machine 90
serves to blow away the chaff and waste
which with the grain travel upon the screen
13 toward the lower end 21 thereof when
the device is longitudinally oscillated as by
means of a pitman 22 herein illustrated by 95
dotted lines adapted for connection with
any suitable moving part of the operating
mechanism of the thrashing machine.

A grain saver is provided adjacent the lower end of the screen 13, consisting of a 100
metallic shelf 23 beneath the foraminous
member 24 of the screen 13 and oppositely
inclined whereby grain passing through the
foraminous member 24 beyond the sides 10
and 11 falls upon the shelf 23 and by reason 105
of the oscillations of the device the grain
passes to the inclined bottom 12 and is dis-
charged at the lower end 18 thereof for bag-
ging. Suitable cross braces 25 are provided
for the screen 13 and it will be evident that 110
the relative inclination of the screen 13 and
bottom 12 may be changed as found de-

sirable as indicated by dotted lines in Figure 2, of the drawing. The shelf 23 has an end wall 26 engaging the foraminous member 24 at the lower end 21 of the screen 13 so that 5 the shelf 23 collects and saves all of the grain that would be otherwise lost by falling outwardly of this end of the auxiliary spout. The lower end of the shelf 23 is adapted to overlie the upper end of the inclined bottom 12 thereby constituting in reality a continuation of the bottom 12. It will thus be seen that the grain passing from the shelf 23 will fall onto the inclined bottom 12 to be discharged at the lower end 18. By 10 so providing the screen 13 with the shelf 23 the cost of production of the entire device will be greatly decreased. It will alleviate the necessity of providing a bottom 12 and side walls 10 and 11 of the same length 15 as the screen 13 and at the same time will provide a relatively long screening surface 20 for the screen 13.

The complete operation of the invention will be fully understood from this detailed 25 description thereof, and while the form of the invention herein set forth is believed preferable, it will be understood that changes may be made therein without departing from the spirit and scope of my 30 invention.

Having thus described my invention, what I claim as new, and desire to secure by Letters Patent, is:—

1. An auxiliary grain spout comprising 35 side walls, an inclined screen pivoted at its upper end between said walls and extending beyond said walls at the opposite end of the device, an inclined bottom positioned between said side walls and a shelf beneath 40 the lower end of the screen adapted for discharge upon said bottom.

2. An auxiliary grain spout comprising side walls having upper end extensions, upper and lower bolts adjustably connected 45 between said walls, a screen member pivoted upon one of said upper bolts and beneath the other upper bolt extending longitudinally between said walls, an inclined bottom board beneath the screen with its lower end 50 positioned upon one of said bolts beneath said upper pivoting bolt and an inclined shelf beneath the lower end of the screen

overlying the upper end of said bottom board.

3. A grain spout adapted for oscillatory 55 movement comprising sides, a screen of greater length than said sides positioned therebetween, a bolt connected through said sides pivotally engaging the upper end of the screen, an adjusting bolt secured between said sides adjacent the opposite end of the device positioned above said screen, an adjustable bottom board oppositely inclined beneath the screen and a shelf beneath the screen having a discharge end 60 65 above said board.

4. A grain spout adapted for oscillatory movement comprising sides, a screen of greater length than said sides positioned therebetween, a bolt connected through said 70 sides pivotally engaging the upper end of the screen, an adjusting bolt secured between said sides adjacent the opposite end of the device positioned above said screen, a shelf beneath the lower end of the screen 75 having a closed end portion engaging the screen, the shelf being inclined downwardly toward the pivotal end of the screen and a bottom board beneath the screen and shelf adjustably positioned between said sides. 80

5. A grain spout adapted for oscillatory movement comprising sides, a screen of greater length than said sides positioned therebetween, a bolt connected through said sides pivotally engaging the upper end of 85 the screen, an adjusting bolt secured between said sides adjacent the opposite end of the device positioned above said screen, a shelf beneath the lower end of the screen having a closed end portion engaging the 90 screen, the shelf being inclined downwardly toward the pivotal end of the screen, a bottom board beneath the screen and shelf adjustably positioned between said sides, a lower bolt between said sides beneath the 95 pivoting bolt, a bottom board oppositely inclined with respect to the screen positioned beneath the screen with its lower end upon said bottom bolt and adjustable retaining means between the sides beneath the opposite 100 end of said board.

In testimony whereof I affix my signature,

MOSES J. DORAN.
